UNITED STATES PATENT OFFICE.

JACK WILSON, OF CHICAGO, ILLINOIS, ASSIGNOR TO UNIVERSAL DRAFT GEAR ATTACHMENT CO., A CORPORATION OF ILLINOIS.

BRAKE MECHANISM.

Application filed July 3, 1926. Serial No. 120,445.

This invention relates to railway brakes and more particularly to the operating mechanism therefor.

One of the objects of the invention is the provision of new and improved mechanism for manually applying railway brakes which are equipped with means for applying the brakes by compressed air, in the usual manner.

10 Another object of the invention is the provision of new and improved hand operated mechanism for railway brakes together with means for mounting the same on railway cars in such a manner that the same extends a minimum distance below the frame thereof.

Another object of the invention is the provision of a new and improved brake operating mechanism that is cheap to manufacture, easily assembled, efficient in operation, will require a minimum amount of space for its operation, that is rugged and simple in construction, and that is not likely to become deranged, broken or out of order.

25 Other and further objects and advantages of the invention will appear from the following description taken in connection with the accompanying drawings, in which

Fig. 1 is a side elevation of a portion of 30 a railway car showing the invention in position thereon, with parts broken away;

Fig. 2 is a diagrammatic view showing the same construction as that shown in Fig. 1, with conventional brakes;

35 Fig. 3 is a top plan view of the reversible lever and means for supporting the same; and

Fig. 4 is a section on line 4-4 of Fig. 3.

On the drawings, the reference character 40 10 designates a railway car comprising the supporting wheels 11 on which is mounted the underframing of the car, as is usual in such constructions. The underframing includes the longitudinally extending sills 12 and the transversely extending frame members 13 and 14 which may be of channel iron or of any other suitable construction.

The brakes and brake operating mechanism of one of the trucks are diagrammatically shown at 15 in Fig. 2, and comprise the brake cylinder 16, brake lever 17, and suitable connecting mechanism, all of which may be of the usual or any approved construction.

55 Suitable mechanism is employed for man-

ually operating the brakes independently of the power operated mechanism. As shown, an expandible and contractable connection between a brake staff 18 mounted on the end of the car, and the brake lever 17 is employed for this purpose. This connection comprises a reversible lever 21 having a long arm 22 provided with an extended curved winding surface 23 and a short arm 24 about which is trained a brake cable 25 one end of 65 which is suitably anchored as at 26 and the other end of which is operatively connected to the spiral brake drum 27 on the brake staff 18. The reversible lever 21 may be of any approved construction, that shown being substantially like that disclosed in patent to Camp and Bartsch, No. 1,543,470, June 23, 1925, and need not be further described.

In order to prevent undue sagging of the 75 brake cable 25, a brake rod 28 may be employed, one end of which is connected to the cable 25 and the other end of which is connected to the cable or chain 30 which in turn is secured to the winding drum 27. The rod 80 is slidably mounted in suitable guides 31 beneath the car. The cable is connected to the reversible lever as at 32.

In certain types of cars there is not sufficient room beneath the same to mount the 85 reversible lever 21 so that it may swing in a vertical plane in the usual manner. The present invention contemplates the use of suitable means for supporting the reversible lever in a horizontal plane whereby the same 90 may be mounted on cars of various types. As shown, a jaw member 34 is employed for this purpose. This member is preferably though not necessarily provided with a bottom plate 35 the outer end of which is 95 curved downwardly as at 36 for guiding the chain 25 during the operation of the device, and a top member 37 between which the reversible lever 21 is pivotally mounted to swing about the vertical pivot 38. The inner end of the jaw member 34 is pivotally connected to the brake lever 17 by the connector member 39, which is preferably though not necessarily flexible.

While the jaw member 34 is disclosed as 105 being provided with a bottom plate having a curved upstanding flange about all except one side of the same, together with a more or less skeleton top member, it is understood that any suitable form of jaw member may 110

be employed. The form disclosed is, however, preferred, because it protects the parts from below from dirt, gravel, sand and the like caused by the rapidly moving vehicle over the same, and at the same time is not unnecessarily heavy and cumbersome.

Suitable means are provided for movably supporting the jaw member beneath the car. Preferably inclined guides 41 are employed for this purpose, the jaw member being provided with hangers 42 and 43 which slidably engage said guides 41. The guides 41 are inclined downwardly in the direction opposite to that in which said jaw member moves in applying the brakes, whereby when the brakes are released the vibration of the car in running will cause the member 34 to automatically move to brake-releasing position.

The hangers 43 are longer than the hangers 42 whereby the jaw member 34 will be supported at all times in a horizontal position, as clearly shown in Fig. 1, whereby the chain 25 will more readily slide over the plate 35.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

1. In brake mechanism for railway cars, a brake lever, a brake staff, an expansible and contractable connection between said staff and lever, including a reversible lever, a jaw member for pivotally supporting said reversible lever in horizontal position, and inclined supporting means for mounting said jaw member on said car.

2. In brake mechanism for railway cars, a brake staff, a brake lever, an expansible and contractable connection between said staff and lever, said connection comprising a reversible lever, a jaw member for pivotally supporting said reversible lever in horizontal position, inclined supports, and means for slidably mounting said jaw member on said supports.

3. In a railway brake, a jaw element comprising a lower member in the form of a plate, a flange extending about a portion of said plate, a top member secured to said flange in spaced relation to said plate, a pivot extending between said members, a reversible lever mounted on said jaw, and two sets of

hangers extending upwardly from said upper member, said hangers being provided with two sets of aligned apertures for engaging inclined guide and supporting rods.

4. In a railway brake, a jaw comprising a bottom plate, a top member, a connector member for holding said top member and bottom plate in spaced relation, a pivot extending between said plate and member, a reversible lever mounted on said pivot to rotate in a substantially horizontal plane between said plate and member, a brake staff, a brake lever, an expansible and contractible connection between said reversible lever and brake staff and a flexible member for connecting said brake lever to said connector member.

5. In a brake mechanism for a railway car, a brake staff, a brake lever, an expansible and contractable connection between said staff and lever, said connection comprising a reversible lever, a supporting plate a flange extending about the sides and one end of said plate, a top member secured to said flange, a pivot carried by said top member and bottom plate for rotatably mounting said lever, and a flexible connection between said reversible and brake levers.

6. In a brake mechanism for a railway car, a jaw element comprising a plate having a curved flange forming a wall, a top member secured to said flange and extending across said plate in spaced relation thereto, and a reversible lever rotatably mounted between said plate and top member and provided with a groove for receiving an operating cable, the free edge of said plate being curved outwardly to form a guide for said cable.

7. In combination with the underframing of a railway car, brake operating mechanism located beneath said underframing, said mechanism comprising a quick takeup device, inclined supports secured to said underframing, and means for slidably mounting said device on said supports.

8. In combination, a railway car, a brake staff at one end of said car, a brake lever mounted on said car, a quick takeup device, an inclined support, means for slidably mounting said device on said support, said means comprising hangers of unequal length for maintaining said device in a horizontal plane, an expansible and contractable connection between said brake staff and device, and means for connecting said device to said lever.

In testimony whereof I affix my signature.
JACK WILSON.

CERTIFICATE OF CORRECTION.

Patent No. 1,623,295.

Granted April 5, 1927, to

JACK WILSON.

It is hereby certified that error appears in the printed specification of the above numbered patent requiring correction as follows: Page 2, strike out lines 97 to 103, comprising claim 7; same page, line 104, strike out the claim number "8" and insert instead "7"; and that the said Letters Patent should be read with these corrections therein that the same may conform to the record of the case in the Patent Office.

Signed and sealed this 24th day of May, A. D. 1927.

Seal.

M. J. Moore,
Acting Commissioner of Patents.
